(57) **CLAIM**

The ornamental design for a faux stepping stone lid for underground valve box, as shown and described herein.

DESCRIPTION

FIG. 1 is an elevated, perspective view of the faux stepping stone lid for underground valve box in accordance with my invention;

FIG. 2 is a left side elevation view thereof;

FIG. 3 is a right side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines shown in FIGS. 1 and 7 are for illustrative purposes only and form no part of the claimed design.

1 Claim, 3 Drawing Sheets

FIG. 1**FIG. 2****FIG. 3**

FIG. 4**FIG. 5****FIG. 6**

FIG. 7
